X-RAY TUBE

Filed May 9, 1922.

FIG. 1.

FIG.2.

INVENTOR
MONTFORD MORRISON

BY
J. F. Elbert
ATTORNEY

UNITED STATES PATENT OFFICE

MONTFORD MORRISON, OF NEW YORK, N. Y., ASSIGNOR, BY MESNE ASSIGNMENTS, TO
WESTINGHOUSE LAMP COMPANY, A CORPORATION OF PENNSYLVANIA

X-RAY TUBE

Application filed May 9, 1922. Serial No. 559,569.

My invention relates to certain improvements in apparatus for the generation of Roentgen or X-rays.

An object of my invention is the provision of a more efficient X-ray device in which a larger percentage of the generated X-rays may be utilized than in tubes at present employed.

Another object of my invention is the provision of an X-ray tube which does not require a special device for focusing the cathode rays.

Another object of the invention is the provision of an X-ray tube which does not require, for its incandescent cathode, material of such high specific electron emissivity as those now employed.

Another object is the provision of an X-ray tube in which the generation of X-rays will be confined to the area intended for that purpose.

A further object of this invention is the provision of an X-ray tube which may be operated without substantial positive ionization while containing gas at a pressure which would otherwise lead to an excessive amount of gaseous ionization in tubes of the prior art.

A still further object is the provision of shielding means for stray X-rays which may be less expensive and cumbersome than the shielding means now employed.

Other objects of the invention may be perceived from a reading of the following specification.

In the operation of X-ray tubes used for certain purposes, it is desirable, for well-known reasons, to avoid positive ionization of the residual gas within the tube. To avoid a large amount of positive ionization in X-ray tubes at high voltages, it has been proposed to evacuate the tube to the highest possible vacuum. Such a degree of vacuum is partly necessary in tubes of the prior art on account of the locally intense electric fields caused by the presence of structures having sharp edges or surfaces of small radii of curvature. The same degree of vacuum is also partly necessary by reason of the structure of tubes of the prior art in which the electrodes were placed comparatively far apart.

According to my invention, however, other means may be employed for constructing an X-ray tube which will operate without a substantial amount of positive ionization. The means herein proposed comprise partly tube elements having relatively large radii of curvature and partly the disposition of the tube elements in close space relation to each other.

The avoidance of a substantial amount of positive ionization in a tube of my invention is made possible by reason of the fact that the intensity of the electric field or potential gradient, upon which ionization may depend, is reduced to a value insufficient to cause a large amount of ionization. In order to reduce the potential gradient to such degree, I may eliminate structures having sharp points or edges and surfaces of small radii of curvature or I may take advantage of the fact that close spacing of the electrodes allows a higher gas pressure to be used than when the electrodes are far apart. Accordingly, I construct at least one of the electrodes of my X-ray tube and other structures therein in such manner that they shall be free from sharp points and edges and have relatively large radii of curvature or I may place electrodes in close proximity to each other, but, preferably, I dispose the electrodes in close proximity to each other and eliminate from all structures the sharp points and edges which may cause electric fields of such intensity as to result in ionization of the residual gas.

While my invention covers these features 85 boardly, I have found that there is a special construction of the tube elements, hereinafter to be illustrated, which affords the above-mentioned advantages and others in addition thereto.

Although, when the electrodes of an X-ray tube consist of parallel planes, the voltage gradient varies inversely as the distance between the electrodes, it is found that for certain other forms of electrodes, the voltage 95 gradient becomes a minimum for a definite separation thereof. For example, it is well known that the maximum voltage gradient between concentric cylindrical electrodes is a minimum when the outer diameter of the in- 100

terior electrode is equal to a constant times the inner diameter of the outer electrode. This constant is shown to be the reciprocal of the base of the Napierian system of logarithms, the latter being usually designated by the Greek letter epsilon and called "e", the value of which is 2.718+. Accordingly, the electrodes of my present X-ray tube may consist of concentric cylinders, the diameter of the inner electrode being substantially equal to

$$\frac{1}{2.718}$$

times the interior diameter of the outer electrode.

The diameters of the cylinders, however, should be of such size that the spacing between them will be less than that at which a substantial or detrimental amount of ionization will occur with the gas pressure used and the voltage applied to the electrodes. As a specific example, it may be stated that the interior diameter of the outer cylinder may be one centimeter and that, for a minimum potential gradient, the diameter of the inner electrode would then be approximately 3.7 mms., the cylinders being concentrically disposed, the separation would then be about 3.1 mms.

Concentric cylinders are considered the preferred form for the electrodes of my X-ray tube but they may assume other forms in which the voltage gradient between the electrodes is not inversely proportional to the distance between them for all values of space separation or, in other words, the form of the electrodes may be such that the maximum electrical stress or potential gradient between them is approximately a minimum for a certain separation. It will be appreciated that, according to this feature of my invention, a higher gas pressure may exist in the tube without obtaining detrimental positive ionization than when the form and spacing of electrodes now in use are employed. The tubes now in use and referred to herein as tubes having the highest possible vacuum, in order to avoid positive ionization, are illustrated and described in Coolidge Patent No. 1,203,495, issued Oct. 31, 1916, wherein the upper limit of pressure is fixed at 0.6 of a micron.

While, under certain conditions, it is desirable to place the electrodes at a distance resulting in minimum electrical stresses, I do not wish to be confined in this invention to such separation of electrodes, inasmuch as I have provided a construction, as hereinafter shown, which has novel advantages even when the electrodes are disposed at a distance other than that which produces the minimum potential gradient. Such variations of separation may be made, for example, with reference to the degree of vacuum in the tube, in order to properly balance the advantages and disadvantages of a given separation of

the electrodes with a given degree of vacuum.

In tubes of the prior art, a large percentage of the X-rays generated have been wasted by reason of the fact that the construction has been such that the rays have emanated from their source at an angle from the intended objective of the X-rays and from points other than the focal spot. Not only have the wasted rays detracted from the efficiency of the X-ray device, but they have called for expensive shielding means of comparatively large area to prevent them from causing personal injury.

My invention, however, provides means, including a novel form and arrangement of the tube elements, whereby a larger percentage of the X-rays are utilized and whereby the means used to absorb stray X-rays is of comparatively small area, the latter feature serving to simplify the cumbersome and expensive shielding means now employed. The adequacy of shielding means of small area is accomplished by absorbing stray X-rays close to their source, as will hereinafter be more clearly illustrated by reference to a drawing of a specific embodiment of this feature.

In the arrangement of the electrodes, according to my invention, I place a cathode, which may be incandescent if desired, in such relation to an anode that all the high velocity electrons may impinge only where it is desired to have them do so, namely, on the focal spot of the target or X-ray-generating surface. Such arrangement of the electrodes has one embodiment when a cathode is placed within a hollow cylindrical anode. This feature of my invention also obviates the necessity for a focusing device now used in X-ray tubes.

The form of construction in which the cathode is encircled by the anode is also of advantage in that a lower electron density is effected, whereby the liability of causing ionization is diminished.

A further advantage to be derived from my invention resides in the fact that the cathode, which is preferably made incandescent, may be made of a material which has a lower electron emissivity than the materials now frequently employed. This advantage arises from the fact that a cathode of larger area may be utilized in one form of my new type of tube.

The foregoing and other novel advantages will be explained in connection with the accompanying drawings in which,

Fig. 1 is a view in elevation, partly in section, of an X-ray tube embodying my invention; and,

Fig. 2 is a fragmentary view, partly in section, showing a modification of my device.

Figure 1 shows an X-ray tube, partly in section, comprising a spherical evacuated glass envelope 1 having arms 2 and 3 extending at right angles to each other, into which

are sealed, respectively, an anode 4 and a cathode 5, the former having a leading-in conductor 6 and the latter having leading-in conductors 7 and 8, these conductors being 5 preferably free from sharp points and edges. The leading-in conductors of both electrodes and the inactive parts of the electrodes are preferably covered with an insulating material. To the exterior ends of the leading-in 10 conductors of the anode and the cathode are secured, respectively, terminals 9 and 10 having large radii of curvature, such structure being disclosed and claimed in my copending application Serial No. 540,141, filed March 1, 15 1922, X-Ray Tube, which eventuated into Patent No. 1,621,852, March 22, 1927. The anode 4 is a hollow, metallic cylinder shown in longitudinal cross section and has its upper and lower ends 12 and 13, respectively, 20 rounded off to a comparatively large radius of curvature to avoid excessively intense electric fields at those parts, whereby the tendency of the gas to ionize may be reduced. Supported within the envelope 1 by means 25 of a rod 14 secured to the neck 3 is a mushroom shaped element 15, shown partly in section, having a stem 16 around which the cathode 5 is wound in helical form.

The anode may consist entirely of a refractory metal of high atomic weight, or 30 may be a composite metallic body, the inner cylindrical portion of which should consist of a metal of high atomic weight, such, for example, as tungsten, uranium or thorium, 35 since the inner surface constitutes the target from which X-rays emanate, while the outer portion may be a metal having high heat conductivity.

The cathode 5 is shown as a helix placed 40 within the anode 4 and wound around the cylindrical stem 16 of the shielding element and cathode support 15, the longitudinal axis of the stem 16 being coincident with the longitudinal axis of the cylindrical anode 4. As 45 above set forth, the diameter of the cathode 5 may have a definite relation to the interior diameter of the anode 4 so that the voltage gradient between the anode and the cathode may be a minimum, the outer diameter of the 50 cathode being

1
2.718

times the interior diameter of the outer electrode.

The cathode 5 preferably consists of a refractory metal, such as tungsten, so that it may be heated to an electron-emitting temperature by an electric current passing 55 through the leading-in conductors 7 and 8.

The element 15, the vertical axis of which is coincident with that of the anode 4, may be a mushroom-shaped member, the stem 16 of which preferably consists of a refractory insulating material, while the upper or body

portion consists preferably of a metal for the purpose of absorbing X-rays which pass through the upper opening of the anode 4.

Fig. 2 shows the cathode 5 in a modified 70 form, being there illustrated as a ring or toroid placed concentrically with the anode 4 so that the electrostatic pull on the cathode is reduced to a minimum. In this form of construction the stem 16 of the element 15, as shown in Fig. 1, is dispensed with, the cathode 5 being held in position by the leading-in conductors 7 and 8. The leading-in conductors and the filament preferably consist of stout wire so that they may resist the strong 75 electrostatic pull exerted on them and are preferably free from sharp points and edges. 80

During the operation of the tube, a high potential being applied to the anode and the cathode while the latter is incandescent, a 85 stream of electrons proceeds at high velocity from the cathode 5 and impinges on the inner surface of the anode 4 from which X-rays emanate. The portion of X-rays which are directed through the opening in the upper 90 part of the anode are absorbed by the shield 15 which may be comparatively close to the origin of the rays. The rays being absorbed before they have spread out over a large area, the shield 15 need not be so large as 95 when it is attempted to absorb them at a comparatively long distance from their source, which is frequently done. It will be noted that although an opening exists between the anode 4 and the shield 15 X-rays 100 cannot make their escape therethrough since they travel only in straight lines. That portion of the X-rays which is directed towards the lower opening of the cylindrical anode 4 forms a cone directed towards the intended 105 objective and is thereby utilized. It will be appreciated that, by the arrangement here shown, the stray X-rays are absorbed not only by the shield 15 but also by the anode 4.

Attention is also called to another valuable 110 feature of the arrangement of the electrodes herein shown, which consists in so disposing the cathode that substantially all of the high velocity electrons impinge on the surface which it is intended to employ as the X-ray-generating surface. This feature is intended 115 as an improvement over prior X-ray tubes inasmuch as the latter have been so constructed that some of the electrons emanating from the cathode have impinged on other surfaces than that intended as the surface of the 120 target and have thereby resulted in the generation of stray X-rays which not only called for additional shielding means but detracted from the efficiency of the tube.

It is also obvious that by reason of the 125 peculiar disposition of the electrodes relative to each other and to the glass walls of the envelope, bombardment by electrons of the walls of the tube is prevented, thus preventing erosion thereof, thus making the present 130

type of tube particularly suitable for higher capacities.

In the preparation of the tube, the envelope should be exhausted of gases and vapors, means for accomplishing which are well known in the art. The parts constituting the X-ray device, particularly the electrodes, should also be freed from gases and vapors; this may be accomplished, for example, by heating the device to a high temperature in a vacuum and removing the released gases and vapors. The degree of vacuum to which the tube is exhausted or the pressure of the gas admitted should be such that, with electrodes of given form and spacing, no substantial or detrimental amount of positive ionization will occur during the operation of the tube. By detrimental positive ionization is meant that quantity of ionization which during tube operation will be evidenced by fluctuations or instability of the tube discharge current at a given electrode spacing, gas pressure and applied voltage.

While I have herein described a preferred embodiment of the several features of my invention, it is to be understood that modifications of the same may be contrived without departing from the proper scope thereof.

What is claimed is:

1. An X-ray tube comprising a gas-tight envelope, an anode within said envelope, said anode having a passageway extending from one said of said anode to another side thereof, a thermionic electron-emitting cathode adjacent one end of the passageway in said anode, means for absorbing X-rays emerging from the cathode end of said passageway, the other end of the passageway in said anode being free and unobstructed to permit the emission of a solid beam of X-rays therefrom.

2. An X-ray tube comprising a gas-tight envelope, an anode within said envelope, said anode having a passageway extending from one side of said anode to another side thereof, a thermionic electron-emitting cathode projecting within one end of the passageway, the other end of the passageway being free and unobstructed to permit the emission of a solid beam of X-rays therefrom.

3. In an X-ray tube, the combination of a hollow cylindrical anode and a cylindrical cathode positioned within said anode, the diameter of said cathode being substantially equal to the product of the interior diameter of said anode by the reciprocal of the base of the Napierian system of logarithms.

4. In an X-ray tube, the combination of a hollow cylindrical anode and a cylindrical electron-emitting cathode positioned within said anode, the diameter of said cathode being substantially equal to the product of the interior diameter of said anode by the reciprocal of the base of the Napierian system of logarithms.

5. An electrical discharge device comprising an evacuated gas-tight envelope, an electron-emitting cathode within said envelope, an anode having a passageway therethrough and means for shielding one end of said passageway, said shielding means having means for supporting said cathode.

6. An electrical discharge device comprising an evacuated gas-tight envelope, an electron-emitting cathode within said envelope, an anode having a passageway extending from one side of said anode to another side thereof, shielding means adjacent the one end of the passageway, the other end of the passageway being free and unobstructed.

7. An X-ray tube comprising an evacuated gas-tight envelope, a thermionic electron emitting cathode within said envelope, an anode having a passageway therein extending from one side of said anode to another side thereof, means for intercepting X-rays emerging from one end of the passageway, the other end of the passageway being free and unobstructed to permit a solid beam X-ray to freely emerge from the tube.

8. An X-ray tube comprising a gas-tight envelope, a hollow anode within said envelope, means for generating electrons, substantially all of the electrons falling upon the target face of said anode for the production of X-rays, means for preventing X-rays emerging from one end of said anode from being projected outside of said envelope, the other end of said anode being open for the free and unobstructed movements of a solid beam of X-rays from the tube to a point outside of the same.

9. In an X-ray tube, the combination of an evacuated envelope, an electron-emitting cathode and an anode therein, said anode consisting of a hollow body formed of large radii of curvature and having a passageway extending from one side to another side of the anode, a metallic cup-shaped shield adjacent one end of the passageway in said anode to intercept X-rays emerging therefrom, the other end of the passageway in the anode being free and unobstructed to permit a solid beam of X-rays to emerge therefrom and from said tube.

10. A vacuum tube for the production of X-ray comprising an incandescent cathode, an anti-cathode surrounding said cathode at a distance, an evacuated gas-tight envelope enclosing said cathode and anode, a portion at least of said envelope being permeable to X-rays, a shield for intercepting X-rays emerging from one end of said anti-cathode, said shield being remote from the end of the anti-cathode adjacent that portion of the envelope permeable to X-rays.

11. An electrical discharge device comprising an envelope having a gas pressure therein greater than .6 of a micron, electrodes

- comprising a thermionic electron-emitting cathode consisting of a refractory metal wire and an anode within said envelope, the electrodes being spaced apart a distance less than
5 the electrode distance at which a detrimental amount of positive ionization will occur with a given gas pressure and applied voltage, the positive ions playing no essential role in the operation of the device.
- 10 12. An X-ray tube comprising an envelope having a gas pressure therein greater than .6 of a micron, electrodes comprising a thermionic electron-emitting cathode consisting of a refractory metal wire and an anode within
15 said envelope, the electrodes being spaced apart a distance less than the electrode distance at which a detrimental amount of positive ionization will occur with a given gas pressure and applied voltage.
- 20 13. An electrical discharge device comprising an envelope having a gas pressure greater than .6 of a micron, electrodes comprising a thermionic electron-emitting cathode consisting of a refractory metal wire and an
25 anode within said envelope, said anode having surfaces of large radii of curvature preventing excessively intense electrical fields at such surfaces, said electrodes being spaced apart a distance less than the electrode distance at
30 which a detrimental amount of positive ionization will occur with a given gas pressure and applied voltage.
14. An X-ray tube comprising an envelope having a gas pressure greater than .6 of a micron, electrodes comprising a thermionic electron-emitting cathode consisting of a refractory metal wire and an anode within
35 said envelope, said anode having surfaces of large radii of curvature preventing excessively intense electrical fields at such surfaces, said electrodes being spaced apart a distance less than the electrode distance at
40 which a detrimental amount of positive ionization will occur with a given gas pressure and applied voltage.
- 45 15. In an electron discharge device which during operation produces X-rays, the combination of an envelope, a thermionic electron-emitting cathode and an anode having an X-ray generating surface within said envelope, and X-ray shielding means having a part thereof integral with said anode and disposed in said envelope for absorbing all of the X-rays except a useful beam thereof.
- 50 16. In an X-ray tube, the combination of an envelope, a thermionic electron-emitting cathode and an anode having an X-ray generating surface within said envelope, and X-ray shielding means having a part thereof integral with said anode and disposed in said envelope for absorbing all of the X-rays except a useful beam thereof.
- 55 In testimony whereof, I have hereunto subscribed my name this 5 day of May, 1922.
- 60 65 MONTFORD MORRISON.
